UNITED STATES PATENT OFFICE.

GEORGE W. BAKER, OF CLEVELAND, OHIO.

EMBROIDERY ATTACHMENT FOR SEWING-MACHINES.

SPECIFICATION forming part of Letters Patent No. 250,037, dated November 22, 1881.

Application filed February 15, 1881. (No model.)

To all whom it may concern:

Be it known that I, GEORGE W. BAKER, of Cleveland, in the county of Cuyahoga, State of Ohio, have invented a new and useful Improvement in Embroidery Attachments for Sewing-Machines; and I declare the following to be a full, clear, and exact description of the same, such as will enable others skilled in the art to which it pertains to make and use it, reference being had to the accompanying drawings, which form a part of this specification.

My invention consists in a novel combination, in a sewing-machine attachment, of devices for forming chain-loop embroidery, and for laying the same in position to be stitched to a fabric by the stitching-needle of a sewing-machine, as will be hereinafter fully described, and pointed out in the claim.

In the drawings, Figure 1 is a front view, showing the hooked needle with the previous loop strung back upon its shank and ready to take a new loop. Fig. 2 is the same, showing the new loop formed and the previous loop passed off the needle over the new loop. Fig. 3 is a view at right angles with the other views. Fig. 4 is a view of the chain-loop formed by the embroidering attachment, and showing, also, a few sewing-machine stitches, by which the embroidery is simultaneously sewed to the goods.

A is a sewing-machine; B, the needle-bar; C, the pressure-bar, all of ordinary construction, the peculiar construction of the machine constituting no part of this invention.

My embroidery attachment is constructed as follows:

D is a frame or bracket, adapted to be fastened at d to the pressure-bar or its foot. D' is a projecting arm. At d' is pivoted a lever, E, the lever-arm E' of which projects down to the vicinity of the needle and close to the fabric, and is provided with an eye for the embroidery-thread at its extremity. A short arm, E², projects so as to engage with a lug on the looper-bar.

F is a bar, which for the purposes of this specification I term the "looper-bar." It is pivoted at f to the bracket D, and is provided with a cam-slot, f', which engages with a stud, F', projecting from the needle-bar. At the lower end of the looper-bar is a needle con-

structed upon the same principle as an ordinary knitting-machine needle, there being a shaft, G, with a hooked end, g, for catching the thread, and a latch, g', for closing over the hook, so as to permit the loop already on the bar to slide off over the new loop. This looper-bar, by reason of the engagement of its cam-slot f' with the stud F', is caused to advance and recede from side to side as the needle-bar is operated. The looper-bar has a lug, f², which engages with the short arm E² of the lever E. A spring, H, brings the lever E back when it has been deflected by the lug f².

A tension device may be provided upon the attachment for the embroidery-thread, though it is not absolutely essential that it should be provided on the attachment. The one shown in the drawings I have found in use to be very effective. It consists of a swelled washer, J, a spring, J', screw-stem J², and tension-nut J³, there being nothing new in the construction of it.

The operation of the device will now be understood. The attachment having been applied to the machine and threaded, as shown, with the embroidery-thread K, the machine is started. The needle, in descending through the fabric, causes the embroidery-needle G to cross over to the left and back of the needle. Its hook engages the thread K, and as the needle rises draws it back, forming a loop. At the same time the lever-arm E' advances in the direction of the feed, carrying the thread K with it, so that when the needle again descends it passes down back of the thread, and so stitches it to the fabric. As the needle, however, descends the embroidering-needle G again crosses over to the left, again engages the thread K, and at the same time, by passing through the loop already upon it, strings the latter back upon the heel of the needle. Now, as the needle B rises the embroidery-needle is again drawn back with its new loop, and as the needle draws out through the loop at its heel this latter loop comes in contact with the little catch g', tilts the latter over so as to cover the hook and permit this first loop to pass off over the new loop. By a repetition of the operation a third loop is formed, the second loop forces back the latch g', takes its place at the heel of the needle G, and then, sliding forward, closes down the latch and passes off into the second

loop, and so on, thus making a continuous chain-loop embroidery, while the machine continually stitches it to the fabric as rapidly as formed.

- 5 It is apparent that if the fastening-thread be of a different color the stitches will constitute a very marked ornamental constituent of the embroidery. So, also, whether of the same or of a different color. If it is large it will assist 10 materially, as shown in Fig. 4, in making, with the regular chain-loop embroidery, a heavy and handsome combination.

In case the operator should desire to make simply the embroidery for use elsewhere, all 15 that need be done is to remove the sewing-machine threads and use only the embroidery-thread. The machine will then make the embroidery alone, and without stitching it to the fabric, and it can be used where desired. It is 20 not essential that this should be attached to the pressure-bar, for it may be connected with any other part—as, for instance, the head of the machine. I prefer, however, to attach it to the pressure-bar, for it then always has the same

relative position with respect to the goods, 25 whether the latter be thick or thin.

I am aware that there has heretofore been combined with a sewing-machine an embroidery attachment connected with the pressure-bar and needle-bar, and arranged to lay chain-loop embroidery-strokes in position to be sewed to a fabric by the stitching-needle, and I do not claim such invention, broadly.

What I claim is—

The combination, with the needle-bar having 35 the laterally-projecting stud, of the slotted looper-bar pivoted to a fixed support and carrying at its lower end the latch-needle, its upper end being provided with a lug, f^2 , and the pivoted lever E, having the arm E² in the path 40 of said lug, and carrying the thread-arm E', substantially as described.

In testimony whereof I sign this specification in the presence of two witnesses.

GEORGE W. BAKER.
